UNITED STATES PATENT OFFICE.

FREDERICK S. RUDGE, OF BROOKLYN, NEW YORK.

DEVICE FOR SECURING FERRY-BOATS.

SPECIFICATION forming part of Letters Patent No. 425,634, dated April 15, 1890.

Application filed December 23, 1889. Serial No. 334,721. (No model.)

To all whom it may concern:

Be it known that I, FREDERICK S. RUDGE, a citizen of the United States, residing at Brooklyn, in the county of Kings and State 5 of New York, have invented certain new and useful Improvements in Devices for Securing Ferry-Boats; and I do hereby declare the following to be a full, clear, and exact description of the invention, such as will enable others 10 skilled in the art to which it appertains to make and use the same.

My invention relates to improvements in devices for automatically securing and releasing ferry-boats; and it has for its object the 15 provision of a very simple and efficient device by which the ferry-boat will be automatically secured to the slip or wharf as it approaches the same, and which can be easily operated by the pilot to release the boat.

20 The invention consists in certain novel features hereinafter described and claimed.

In the annexed drawings, which fully illustrate my invention, Figure 1 is a perspective view of the coupling hook or ring attached to 25 the wharf. Fig. 2 is a similar view of the pivoted block or coupling-pin on the boat, showing it engaged by the coupling-ring. Fig. 3 is a view showing the manner of operating the device to release the boat. Fig. 4 30 is a perspective view looking at the rear end of the box or support for the coupling-hook.

In carrying my invention into practice I secure to the wharf or ferry-slip a box or support A, which may be of any suitable size 35 or material, and is provided in its upper side with a longitudinal V-shaped groove B, as shown, in which the coupling-hook C rests. At the rear end of the box or support I provide the vertically-adjustable standard or 40 supporting-plate D, which is mounted between the rearward extensions E of the box or support and is secured at any desired height by the bolts F, which are mounted on the extensions E and engage perforations or sockets G 45 in the plate or standard. The said plate or standard is further provided with one or more openings H, through which the shank or body of the coupling-hook passes, and chains I are secured at their upper ends to the inner or 50 rear side of said plate and have pins J attached to their lower ends. Similar chains K

are provided on the front side of the plate and have pins L at their lower ends.

The coupling hook or ring M consists of a bar or shank N, having an eye or loop at its outer or front end and provided with the longitudinal series of openings P near its rear end. The bar or shank rests in the groove B and projects through one of the openings H in the vertical plate or standard, 60 so as to be supported in proper position to engage the coupling-pin on the boat. The coupling hook or ring is secured in position by inserting the pins J and L through the openings P, so that they bear against the 65 front and rear sides of the plate, thus preventing the hook from having any endwise or longitudinal motion. The hook is supported and secured in the event of the chains J and K being unfastened by the chain Q, which 70 has its ends secured to the upper front corners of the box or support A by spring-hooks and its central portion passed through a ring R on the coupling-hook.

The coupling-pin S is pivoted in a slot T in 75 the floor or deck of the boat, and has its upper and lower ends extending, respectively, above and below the deck. The upper end of the pin is cone-shaped, as shown at V, so as to provide a deflecting surface, up which the end 80 of the coupling-hook may ride and pass over the end of the pin to engage the same. The rear side of the pin, at the upper end thereof, is provided with a series of notches or shoulders, which engage the coupling-hook in the 85 operation of the device to prevent the accidental and premature release of the boat. Below its pivot the coupling-pin is provided with a slot or notch W, which is engaged by the end of a lever Y, pivoted on the under 90 side of the deck. The opposite end of this lever is connected by a pitman Z with a vertically-disposed lever a, which extends up into the pilot-house.

In practice the coupling-hook rests loosely 95 in the bottom of the groove in the box-support A and projects from and beyond the front end of the same, while the coupling-pin is arranged normally in a vertical position and held in such a position by the end of the 100 lever Y engaging the notch W, as will be readily understood upon reference to the

drawings. As the boat approaches the wharf the coupling-hook will ride upon the deck and over and into engagement with the coupling-pin, thereby securing the boat. If it is desired to release the boat, the pilot throws the vertical lever backward, thereby vibrating the horizontal lever, so as to release the same from the coupling-pin, when the strain applied to the pin by the boat moving from the wharf will cause it to swing on its pivot into a horizontal position, so that it may readily pass under the coupling-hook. While the boat is making its trip the coupling-pin is returned to its normal vertical portion, and the lever then again engaged in the notch in the pin, so that when the boat approaches the other wharf it may be automatically secured thereto.

It will be observed from the foregoing description that I have provided a very cheap and simple device by which the boat will be effectually secured to the wharf, and which is entirely automatic in its operation. By the use of my device the boat can be very quickly secured without necessitating the attendance of operators, thus effecting an economy of time and labor. The series of shoulders or notches in the upper end of the coupling-pin provides for a positive engagement of the coupling-hook, notwithstanding any difference that may exist between the heights of the wharf and the deck of the boat. The vertical supporting plate or standard can be quickly and easily adjusted to correspond to the tide, and the manner of supporting the coupling-hook permits it to readily rise and fall in the operation of the device.

It will be understood, of course, that I do not limit myself to the exact details of construction shown in the drawings, as it is obvious that many minor changes may be made therein without departing from the principles of my invention.

Having thus described my invention, what I claim, and desire to secure by Letters Patent, is—

1. A device for securing ferry-boats, consisting, essentially, of a coupling-hook secured to the wharf, a pivoted coupling-pin carried by the boat and adapted to be engaged by the coupling-hook, and means for operating the coupling-pin, as set forth. 50

2. The combination of the vertically-adjustable supporting-plate mounted on the wharf, the coupling-hook carried thereby, and a coupling-pin carried by the boat and adapted to be engaged by the coupling-hook, as set forth. 55

3. The combination of the coupling-pin pivoted in the deck of the boat and having a notch in its side below its pivot, the lever engaging said notch, means for releasing said lever, and the coupling-hook mounted on the wharf and adapted to engage the coupling-pin, as set forth. 60

4. The combination of the pivoted coupling-pin in the deck of the boat, having a series of notches on its rear side in its upper end, means for operating said pin, and the coupling-hook mounted on the wharf and adapted to engage the notches in said pin, as set forth. 70

5. The combination of the box or support secured on the wharf and having a longitudinal groove in its upper side, the coupling-hook resting in said groove, the chains secured to the box and the hook, and the pin on the boat adapted to be engaged by the hook, as set forth. 75

6. The combination of the box on the wharf, the vertical plate adjustably secured to the rear end of the box, the coupling-hook adjustably secured to said plate and supported by the box, and the pin carried by the boat and adapted to be engaged by the said hook, as set forth. 80

In testimony whereof I affix my signature in presence of two witnesses.

FREDERICK S. RUDGE.
